UNITED STATES PATENT OFFICE

ARTHUR L. DUNHAM, OF TOMPKINSVILLE, NEW YORK

METHOD AND APPARATUS FOR STERILIZING

Application filed June 22, 1929. Serial No. 372,848.

This invention relates to improvements in methods of sterilizing and apparatus therefor. Its object is to provide an effective method of sterilization by the use of superheated steam, which shall be effective and inexpensive, and to provide suitable apparatus for sterilizing by this improved method. According to the present invention, the sterilizing is effected in a closed chamber 10 which is heated to a desired temperature by the introduction of superheated steam at comparatively low pressure. The sterilization takes place in a dry atmosphere and so it is desirable to maintain the temperature 15 within the chamber above the point of steam condensation.

I will describe my invention in the following specification, making use of a drawing which shows a sterilizing chamber in sectional elevation, and with the parts which 20 cooperate with it shown more or less diagrammatically, and will point out its novel features in appended claims.

In the drawing, 10 designates a pipe leading 25 from a steam supply line into a superheater 11, from which it is led by a conduit 12 to the sterilizing chamber. If desired, the pressure and the temperature within the superheater may be regulated by some such 30 means as those shown in Patent No. 1,398,-503, which was issued to me on November 29, 1921. It is not necessary, according to my invention, to use the superheated steam at a pressure much above atmospheric pressure, as it is only necessary to maintain a 35 flow of the superheated steam through the sterilizing chamber and to insure a penetration of the hot steam into the article or goods treated. The larger diameter of the 40 conduit 12, compared to that of the pipe 10, is intended as a diagrammatic representation of a means for reducing the pressure of the superheated steam.

20 is an insulated chamber, open at one 45 end for the reception of the articles to be

sterilized and having a closure 21 for such opening. 22 is a shelf for supporting the articles. The conduit 12 is connected with a plurality of expansion nozzles 13 suitably positioned within the chamber. 50

The superheated steam passes out of the chamber through pipes 14, in which are valves 15, by means of which the pressure in the chamber may be raised, if desired, and the rate of its flow controlled. These valves 55 may be actuated automatically by a pressure regulator 16.

It is desirable to keep the atmosphere within the chamber dry and for that purpose a heating coil 30 may be provided, connected with the steam supply by a pipe 31 and exhausting at 32. 33 is a thermostat arranged to control a valve 34 in the pipe 31 automatically. By this means the temperature within the chamber 20 may be maintained 60 above the point of condensation of steam. 65

This apparatus may be large or small and capable of sterilizing the largest to the smallest articles from hairpins to bedsteads 70 and mattresses. Articles placed within the chamber 20 and subjected therein to the high temperature of superheated steam in continuous motion, become thoroughly sterilized in a very short time. The sterilization 75 is effected by the liberation of heat units. This method may be practiced with other apparatus than that shown and the apparatus itself may be modified greatly without departing from the spirit and scope of the 80 invention, as defined in the appended claims.

What I claim is:

1. The herein described method of sterilizing, which comprises raising the temperature of a closed chamber at least to the point 85 of condensation of steam, placing an article to be sterilized in said chamber, passing a current of superheated steam through the chamber, and maintaining a desired constant pressure within the chamber. 90

2. The herein described method of sterilizing, which comprises placing an article to be sterilized in a closed chamber, maintaining the temperature within the chamber above the point of condensation of steam, and passing a current of superheated steam through the chamber. 80
3. The herein described method of sterilizing, which comprises placing an article to be sterilized in a closed chamber, maintaining the temperature within the chamber above the point of condensation of steam, passing a current of superheated steam through the chamber, and maintaining a desired constant pressure within the chamber. 85
4. A chamber provided with an opening for the introduction of an article to be sterilized, means for closing the opening, a source of superheated steam, means for passing a current of superheated steam into the chamber, and an adjustable outlet for the superheated steam. 90
5. A chamber provided with an opening for the introduction of an article to be sterilized, means for closing the opening, means for raising the temperature within the chamber, a source of superheated steam, and means for passing a current of the superheated steam into and out of the chamber. 95
6. A chamber provided with an opening for the introduction of an article to be sterilized, means for closing the opening, means for raising the temperature within the chamber, a source of superheated steam, means for passing a current of the superheated steam into the chamber, and an adjustable outlet for the superheated steam. 100
7. A chamber provided with an opening for the introduction of an article to be sterilized, means for closing the opening, a steam coil for raising the temperature within the chamber, a source of superheated steam, an inlet for passing a current of the superheated steam into the chamber, and an adjustable outlet for the superheated steam. 105
8. A chamber provided with an opening for the introduction of an article to be sterilized, means for closing the opening, a steam coil for raising the temperature within the chamber, a source of superheated steam, an expansion nozzle for passing the superheated steam into the chamber at low pressure, and an adjustable outlet for regulating the escape of the superheated steam. 110
9. A chamber provided with an opening for the introduction of an article to be sterilized, means for closing the opening, a steam coil for raising the temperature within the chamber, temperature actuated means for controlling the circulation of steam in said coil, a source of superheated steam, an expansion nozzle for passing the superheated steam into the chamber at low pressure, and 115
10. A chamber provided with an opening for the introduction of an article to be sterilized, means for closing the opening, a steam coil for raising the temperature within the chamber, temperature actuated means for controlling the circulation of steam in said coil, a source of superheated steam, an expansion nozzle for passing the superheated steam into the chamber at low pressure, an outlet for the superheated steam, and pressure controlled means for automatically adjusting the outlet. 120
